CAR ROOF.

APPLICATION FILED SEPT. 1, 1914.

Patented May 28, 1918.

2 SHEETS—SHEET 2.

UNITED STATES PATENT OFFICE.

THOMAS NATHAN RUSSELL, OF CHICAGO, ILLINOIS, ASSIGNOR TO CHICAGO-CLEVELAND
CAR ROOFING COMPANY, A CORPORATION OF ILLINOIS.

CAR-ROOF.

1,267,908.

Specification of Letters Patent. Patented May 28, 1918.

Application filed September 1, 1914. Serial No. 859,676

To all whom it may concern:

Be it known that I, THOMAS NATHAN RUSSELL, a citizen of the United States, residing in Chicago, in the county of Cook and State 5 of Illinois, have invented a new and useful Improvement in Car-Roofs, of which the following is a specification.

My invention relates to outside metal roofs for railway cars, and has for its principal 10 objects to improve the strength and rigidity of the roof frame; also the attachment for movably confining the main or flat portions of the eaves ends of the roof sheets, whereby the joint incident thereto is made proof 15 against leakage and minor accidents; and also to improve the construction and functions of the seam clip whereby the roof sheet seam is confined.

The invention consists in the parts and 20 combinations thereof hereinafter set forth and claimed.

In order to make the invention more clearly understood I have shown in the accompanying drawings means for carrying 25 the same into practical effect, without limiting my improvements, in their useful applications, to the particular construction which, for the purpose of example, I have delineated. In the said drawings—

30 Figure 1 is a transverse vertical section, showing one half of a car roof embodying the invention.

Fig. 2 is a side view of a portion of the same.

35 Fig. 3 is a vertical transverse section of the same, showing the eaves portion of the roof and supporting frame parts on a larger scale.

Fig. 4 is an outside end view of the car- 40 line, the Z-side plate being shown in dotted lines.

Fig. 5 is a detail vertical section trans- 45 versely of the car showing the use of pur- lin, and the construction of the side seam which united the roof sheets.

Referring to the drawings, A indicates the side plate of Z-bar form in cross section, having a top inner horizontal flange 1, a vertical web 2 and an outer bottom hori- 50 zontal flange 3. 4 is the ridge pole, and 5 the carlines, the latter being of Z-bar form in cross section having a top horizontal flange 6, a vertical web 7 and a bottom horizontal flange 8. Each carline extends preferably 55 across the car, from side plate, to side plate,

and is attached to the ridge pole by a bolt 9, passing up through the flange 8 of the carline. At its outer end the flange 6 passes under the flange 1 of the side plate and is attached thereto by one or more rivets 10, the web 7 is bent parallel with the web of the side plate and is attached thereto by one or more rivets 11, and the flange 8 abuts the said web 2 of the side plate. To accommodate this construction the carline flanges 6 and 8 are cut off flush with the inner face of the side plate web and the web 7 is bent as described.

12 is a wood filler carried by the carline and arranged to support the top sheathing 70 13. This filler may rest on the bottom flange 8 of the carline and be attached by bolts 14 to its web 7. At its ridge end the filler abuts the ridge pole 4.

15 is a wood filler fitted to the top of the 75 top side plate flange 1, and attached thereto by bolts 16, the filler being recessed at 17 for the heads of the bolts, and the latter passing preferably also through the top web of the carline. The filler is also recessed along its outer edge at 18 to receive the eaves strip 19.

20 indicates posts or braces which rise 80 from the car sills (not shown) and support the Z-side plates. The said posts are or may be of Z-bar form in cross section, having an inner flange 21 arranged longitudinally of the car, an outwardly extending web 22, and an outer longitudinally flange 23. The flange 21 is cut off to abut the under side of the bottom side plate flange 3, the web 22 is bent parallel with said flange and attached thereto by a rivet 24, and the flange 23 is bent inwardly parallel with the flange 3 and attached thereto by a rivet 25. So far as are 85 concerned other features of my invention, the posts 20 may be of U-form in cross section, having their outer longitudinal web cut off to abut the under side of the flange 3 and their two outwardly extending webs 90 bent forward and rearward respectively, parallel with the under side of the flange 3 and attached thereto by rivets similar to the rivet 24.

The side sheathing is shown at 26, consisting of matched boards arranged horizontally across the inner faces of the flanges 21 and secured thereto by bolts 27, the said sheathing extending up far enough to lap the inner side of the side plate web 2.

28 is the side fascia fitted on the outer side of the web 2 and the outer edge of the filler 15, and extending up to about the level of the bottom of the recess 18. Attached to the 5 inner side of the fascia is the vertical flange 29 of the eaves strip 19, preferably by nails 30. After the fascia is applied as described, and so that the bottom flange 31 and the hook flange 32 of the eaves strip are properly located in the recess 18, it is secured in place by bolts 33, which pass to the inner side of the web 2 and preferably through the bent end of the earline web 7.

34 indicates the roof sheets bent at their 15 transverse edges to interlock and form upstanding seams 35. They are also bent at the ridge end to form a suitable ridge seam 36, and at their eaves ends are bent under to form hook flanges 37 which interlock with 20 and under the hook flanges 32 of the eaves strip.

38 is an eaves flashing inclosing the upper part of the fascia and formed with an inwardly extending flange 39 which enters 25 the recess 18, over the bottom flange 31 and under the hook flange 37 and between the said flanges. The flashing is attached to the outer side of the fascia by nails 40, and is also overlaid by the shanks of the roof 30 sheet seam clips 41.

The said clips 41 are malleable castings formed with a top inward projection 42 which extends over the seam 35 and confines the same from upward displacement. At 35 the plane of the roof the clips are formed with two inwardly extending projections or fingers 43 which lie immediately at the sides of the seam 35 and confine it, and also hold the roof sheets down on the top sheathing. Between the projection 42 and the fingers 43 the clip is formed at its sides with openings 44 which extend outward past the eaves end of the seam 35, thereby 40 allowing free escape of cinders and dust and moisture, which would otherwise accumulate and cause the rotting of the roof 45 sheets in proximity to the clips. The outer parts of the fingers 43 are also elevated above the flashing 38 so as to leave forward 50 and rearward openings 45, for the same purpose with respect to the flashing. These eaves connections produce not only a very strong and secure but a very durable roof. The outer part of the clip 41 is extended

downward, along the outer side of the fascia 55 end of the flashing 38, in the form of widely separated front and rear legs 46 which are perforated for securing bolts, and nails 47. For this purpose the bolts 33 are or may be used. The space between the legs 46 is extended upward above the top of the flashing 38 so as to provide an escape opening 48 directed laterally outward and co-operating with the openings 44 and 45 for the described purpose.

The said wood filler 15 on its inner edge may match and interlock with the top sheathing, as shown, and it confines the top sheathing, and is confined by the fascia.

If the top sheathing boards are to run 70 transversely of the car the filler bars 12 may be replaced by one or more purlins 49, as seen in Fig. 5.

What I claim is:

1. In an outside metal car roof, in combination: side plates formed of Z-bars having inwardly extending top flanges, vertical webs and outwardly extending bottom flanges; earlines carried by and beneath the said inwardly extending flanges; top sheathing 80 carried by the earlines; a wooden filler bar fitted and secured on the top flange of the side plate and confining the outer edge of the top sheathing; a side fascia attached to the vertical web of the side plate and extending up and confining the outer edge of the said filler bar; and roof sheets extending over the top sheathing and the said filler bar, substantially as specified.

2. A roof sheet seam clip for car roofs, formed with a top inwardly extending projection to confine the top of the seam, inwardly extending fingers to engage on the top of the roof sheet at the sides of the seam, and with front and rear openings at the outer ends of the said projection and fingers, and with widely separated front and rear legs adapted to be attached to the side of the car and having between them a space extended upward to near the top of the clip; 95 substantially as specified.

In testimony whereof I affix my signature in presence of two witnesses.

THOMAS NATHAN RUSSELL.

Witnesses:

R. C. DUDLEY,

HENRY LOVE CLARKE.
